UNITED STATES PATENT OFFICE

JOHN B. CROFOOT, OF ARLINGTON HEIGHTS, ILLINOIS

STAPLING MACHINE

Application filed May 4, 1928. Serial No. 274,988.

My invention relates to stapling machines of the magazine type adapted to receive staples in strips for individual attachment to papers, boxes and the like.

More particularly my invention contemplates a stapling machine of the spring actuated type, with improved means for the actuation of the device together with practical conveniences consequent to the adoption of the structure employed.

The object of my invention is to provide a device of the kind described, convenient of operation, positive in action, and durable of wear.

Another object is to provide a stapling machine with novel means insuring the ejection and use of the last staple of a strip of staples, thereby obviating jamming and clogging of the machine.

Additional objects and advantages of the method in construction herein employed will appear more fully in the herein specification when taken in connection with the accompanying drawings in which:

Figure 1 is a sectional view, partly in elevation, of a stapling machine embodying my invention.

Figure 2 is a top plan view thereof.

Figure 3 is a sectional view taken on line 3—3 of Figure 1.

Figure 4 is a sectional view, partly in elevation of a stapling machine similar to that shown in Figure 1, the operating handle being depressed, showing the plunger about to be released.

Figure 5 is a sectional view taken on line 5—5 of Figure 4.

Figure 6 is a fragmentary sectional view of a modified form of my invention.

In the drawings wherein similar characters of reference indicate corresponding parts in the several views, 11 designates the handle of my stapling machine, to which is pivotally secured by the pin 12, the operating lever 13 which has riveted thereon a hand grip 14 on which is attached by pin 15 a tension spring 16, the other end of the spring 16 being hooked over the pin 16' on the upper part of the handle 11.

Forming an integral part of the handle 11,

is a barrel 17, having a bore 18, whereon reciprocates a plunger 19 to the top of which is secured an annular member 20, having a pair of pockets 21, 22 accommodating the ends of springs 23, 24, which are secured therein by pins 25, 26 respectively. The other ends of the springs 23, 24 lie within longitudinally extending pockets 27, 28 in the barrel 17, being secured in the pockets by other pins 29, 30,—these elements being best shown in Figure 5 wherein the barrel 17 together with bore 18 and plunger 19 are shown surmounted by a cap 31 which is secured to the handle 11, by screws 31'.

The plunger 19 as shown in Figures 1 and 4 is provided with a cam 32 secured to a pin 33 and rockably mounted thereon in an arcuate notch 34. The cam 32 has a recess 35 to accommodate a spring 36 which seats in the pocket 37 in the plunger body, the spring serving to impel the cam into offset position whereby engagement is had with the heel 38 of the operating lever 13 until the heel on its upward swing passes over the point of the cam, as shown in Figure 4, and then permits the latter and consequently the plunger 19 to be propelled forcibly downward under the tension of springs 23 and 24. The plunger in its descent engages and cuts off one of the staples from the strip 39 which latter lies within a magazine chamber 40, over a guide member 41, being fed forward a staple at a time by the point of feed pawl 42 which is secured to sliding bolt 43, which has a slot 43' accommodating the pin 44 of the handle 11. The bolt 43 is impelled by a spring 44', the heel 45 of the bolt being adapted to enter into notch 45' of plunger 19 when the latter rises with the depression of operating lever 13 to a point where the notch engages the heel of the bolt. As best shown in Figures 1 and 4 the feed pawl 42 has a spring 42' secured thereto, this spring lying within a pocket 46 of the bolt 43, being secured to pin 51.

As best shown in Figure 3, it will be seen that the point of feed pawl 42 consecutively engages one at a time the center row of holes 47 of the strip of staples 39,—the feeding action being accomplished after the pawl 42 is retracted when the plunger 19 descends to

cut off an individual staple. The forward movement of this pawl occurs when the plunger is ascending preparatory to the release and tripping of the cam of the plunger.

5 Referring again to Figures 1 and 4, 48 designates a hold back pawl whose function is to permit the advance of the strip of staples one at a time, and to maintain same in position for the next feeding movement of the pawl 42.

10 As will be seen in these figures the hold back pawl is likewise mounted on a pin 48' secured to a part of the handle 11, and is impelled into operative engagement with the stapling strip by means of the spring 49.

15 The function and mode of operation of the embodiment of my invention shown in Figures 1 to 5 inclusive has been, in large part indicated by the foregoing description, but will now be made more fully apparent by

20 the following brief explanation: assuming that a strip of staples has been inserted in the magazine chamber 40, to the position shown in Figures 1 and 4, when the operating lever 13 is depressed, it will be observed the upward

25 movement of the plunger 19 will permit one of the staples to enter the bore 18 under the influence of feed pawl 42. As indicated above when the heel 38 of the operating lever swings past the point of cam 32, the plunger 19 will

30 be driven downwardly with considerable force by the springs 23, 24. The bottom of the plunger 19 engaging the strip protruding into the bore will cut off same in the customary manner and secure the strip to the articles de-

35 sired. The function of the hold back pawl is merely to hold the strip in position while the point of the feed pawl returns to engage another hole.

With reference to the embodiment shown in 40 Figure 6, it will be observed that I have provided the feed pawl with an additional arm 50. The function of the additional arm is an important one in that it provides a means in cooperation with the arm of the regular 45 pawl 42 of insuring the feeding of the last of a series of staples. This is accomplished as follows: By inspection of Figure 6 it will be noticed that the additional arm 50 will thrust forward into position to be cut off the staple 50 immediately adjacent the bore 18. When this staple has been cut off, it will be noted that the normal arm 42 now ceases to function but that the additional arm 50 will again function to feed into the bore the last staple, 55 which may be driven into the article desired in the normal manner. In Figure 6, for the purpose of illustration it may be assumed that the two staples next adjacent the bore are the 60 last of the strip of staples.

While I have described with particularity a preferred construction, it will be understood that the device is susceptible of variation and change without departing from the 65 spirit or sacrificing any of the advantages of

the invention as defined in the appended claims.

What I claim as new and desire to secure by Letters Patent is:

1. A stapling machine comprising a frame having an integral handle, a yieldingly-held operating lever pivoted to said handle, a plunger having an arcuate recess, a spring-actuated cam mounted on a pin secured to said plunger within the recess, said cam being directly engaged by said lever, means to progressively feed a strip of staples one by one into a bore to be individually sheared off by said plunger, and means including a pair of springs to return said operating lever to normal position after operation thereof, each of said springs being secured in one of a pair of pockets in an integral part of the handle and having a connection to said plunger. 75 80

2. A stapling machine comprising a frame having an integral handle and a barrel with a bore, a plunger in said bore, a plurality of springs contained directly in a pair of pockets integrally formed with said barrel and secured to said plunger, an offset cam mounted in a recessed part of said plunger, a hand-operated lever pivoted to said handle and having direct engagement with said cam, means to feed a strip of staples from a magazine forming a part of the frame, and means to return said operating handle to position after manipulation thereof. 90 95

3. A stapling machine comprising a frame having an integral barrel having a bore and a magazine chamber, a plunger slidable in said bore, an annular member secured to said plunger, a pair of pockets in said barrel, a spring in each of said pockets, said springs being secured to said annular member, a spring pressed bolt engaging said plunger, and a feed pawl actuated by said bolt in a manner to thrust a series of staples in the form of a strip, one by one into the path of said plunger, said pawl being adapted to insure the ejection of the last of a series of staples, substantially as described. 100 105 110

4. A stapling machine comprising a unitary frame including a barrel having a bore therein and a groove accommodating a strip of staples, a plurality of spring accommodating pockets in said barrel one on each side of said bore, a plunger slidable in said bore, a member carried thereby, springs secured to said member and received in said pockets, mechanism actuated by said plunger for feeding a staple strip so as to dispose the end staple of the strip in said bore, an operating lever adapted to raise the plunger in a manner to tension said springs, said lever tripping said plunger at a given point in its ascent, and means to return the operating lever to normal position after said plunger has been tripped. 115 120 125

5. In a stapling machine comprising a frame, an operating handle, a staple-contain-

ing magazine, a shearing spring-propelled plunger, a spring-pressed bolt engaging said plunger, and a combination feeding pawl mounted on said bolt, said pawl including two arms, one of said arms serving to normally feed staples on a strip, one at a time, to the action of the plunger, the other of said arms serving to eject the last staple of a strip of staples.

10 6. In a stapling machine comprising a frame, an operating handle, a staple-containing magazine, a shearing spring-propelled plunger, and a plurality of pawls within said frame, one of said pawls acting to prevent retractive movement of the staples within the magazine, the other of said pawls having a pair of arms pivoted thereto, one of said arms serving to eject the last of a series of staples on a strip from the magazine, the other of said arms operating to feed the staples one at a time to the action of said plunger.

7. A stapling machine comprising a frame having an integral barrel having a pair of pockets one on each side of a central bore, a tension spring secured in each of said pockets, a member attached to both of said springs, a plunger carrying said member, a spring pressed cam pivoted on said plunger, an operating handle to engage said cam in order to raise the plunger against the tension of the springs, said cam being released from the operating handle at a certain point in the ascent of the plunger, means operated by the ascent and descent of the plunger to automatically and progressively feed staples one at a time to the shearing of said plunger, and means insuring ejection of the last of a strip of staples, thereby leaving the magazine of the stapling machine free for the introduction of a new strip of staples.

8. A stapling machine comprising a frame having a magazine for the reception of a strip of staples, a casing integral with said frame, said casing having a central bore and a pair of pockets one on each side of said bore, a pair of springs secured in said pockets, a plunger connected to said springs and slidable in said bore, said plunger having a notch, a spring pressed bolt receivable in said notch and having a guide slot receiving a pin secured to the frame, said plunger and said notch cooperating to cause reciprocation of said bolt, a feed pawl pivoted to said bolt, said feed pawl having a pair of arms, one of said arms being for the normal progressive feeding of said strip of staples into the bore, the other of said arms serving as a means to feed and eject the last of said strip of staples into the bore, a spring actuated retention pawl serving to prevent retraction of the strip of staples, and a cap inclosing the bore, part of said barrel and said plunger.

65 9. A stapling machine comprising a frame

having a staple-containing magazine chamber, a spring-propelled plunger having a cam, an operating handle cooperating with said cam and yieldingly maintained in inoperative position by a spring, and a pair of pawls to feed and prevent retraction of a strip of staples within said magazine, one of said pawls having a pair of prongs adapted to engage the outer row of holes of a strip of staples, the other of said pawls having an integral prong engageable in a center row of holes, and an additional prong pivoted on to said other pawl likewise serving to enter into one of the center row of holes, whereby means are provided to feed a strip of staples, one at a time including the last staple by said additional prong, to the action of said plunger, and to prevent retraction of the strip of staples.

In testimony whereof I have signed my name to this specification.

JOHN B. CROFOOT.
